HYDROSTATIC SIPHON CIRCULATION CONTROL FOR THERMOSIPHON HEAT TRANSFER SYSTEMS

Marcus E. Fiene, deceased, late of Scotia, N. Y.,
by Clara E. Fiene, administratrix, Erie, Pa., as-
signor to General Electric Company, a corpora-
tion of New York

Application May 14, 1947, Serial No. 748,150

12 Claims. (Cl. 237—7)

1

The invention relates to thermosiphon heat transfer systems, particularly systems including a boiler or other heated liquid container from which the heat dissipation is to be controlled.

The principal object is to provide improved hydrostatic siphon control means for controlling the thermosiphon circulation of the heat transfer medium.

The improvements of the present invention, while not limited thereto, are particularly advantageous in a hot water boiler heating system for homes, particularly where the boiler heats domestic hot water in both summer and winter and the improved hydrostatic siphon circulation control of the present invention is operated under the control of a room thermostat so as to control the circulation of the hot water to the heat exchanger for heating the rooms in the winter while preventing transfer of heat to the rooms in summer.

Thus, another object is to provide improved thermostatic control arrangements for stopping and starting thermosiphon circulation by rendering a hydrostatic siphon in the thermosiphon system effective or ineffective.

Another object is to provide an improved inverted U-tube siphon-type of thermosiphon circulation control arranged to gas-lock and thereby break the thermosiphon liquid circulating circuit, together with improved hydrostatic liquid level control means for raising and lowering the liquid level in the inverted U-tube siphon so as to selectively start and stop the thermosiphon liquid circulation through the tube and thereby control the heat transfer action.

Further objects and advantages of the invention will appear in the following description of the accompanying drawing in which Fig. 1 is a schematic side view, partly in section, of a hot water boiler furnace thermosiphon heat exchanger system embodying the improvements of the invention in a preferred form; Fig. 2 is a partial sectional view of the heat exchanger shown in Fig. 1; and Fig. 3 is a schematic view of a modified form of thermosiphon heat exchange system embodying the invention.

As shown in Fig. 1, the thermosiphon heat exchange medium circulating system indicated generally by the reference character 10 includes the hot water boiler 11 and the heat exchanger 12 which are interconnected at the bottom by the conduit 13 and at the top by the improved hydrostatic siphon circulation control of the present invention indicated generally by the reference character 14. The boiler furnace 11 is

shown as of the conventional hand-coal-fired type provided with the draft damper 15 and the check damper 16 for regulating the fire. These dampers are shown interconnected in the usual way to be operated by the tilting lever 17 that is actuated by the boiler pressure-responsive bellows 18. The tilting lever 17 also carries a tilting mercury switch 19. Boiler 11 is provided with a domestic hot water heater 21 of the usual form. 10 The heat exchanger 12 consists of a finned tube coil 23 enclosed within the air duct 24 through which the air is circulated by a blower 25 driven by the motor 26 to transfer heat from the coil 23 into the rooms of the house. An automatic 15 air vent valve 27 is provided for venting air from the coil 23.

The improved hydrostatic siphon circulation control 14 for the thermosiphon system consists in the preferred form shown in Fig. 1 of the closed 20 and heat insulated casing 28 through the bottom of which the two conduits 29 and 30 extend so as to form an inverted U-type siphon in the upper leg of the thermosiphon circulating system. The dotted line 31 indicates the normal 25 water level in the hot water boiler 11 and the dotted lines 32 and 33 indicate the corresponding water level in the conduits 29 and 30. Hence, the inverted U-siphon 14 extending above the water level normally introduces a break in the thermosiphon water circulating circuit and thus 30 normally prevents circulation of the hot water from the boiler 11 to the heat exchanger 12.

The steam or vapor space 34 in the top of the hot water boiler 11 is interconnected with the interior of the siphon casing 28 by means of the pressure equalizing pipe 35 that is provided with the normally open electromagnetically closed valve 36 for controlling communication between the boiler vapor space 34 and the interior 35 of the casing 28.

The finned vapor condenser tube 38 is interconnected with the interior of the casing 28 and is located inside a loop 24a extending from the air duct 24 opposite the finned heat exchange coil 23. Preferably the loop 24a is provided with a layer of heat insulating material 39 and also with an air flow barrier 40 so as to insure that heat is released from the finned tube 38 only when air is being circulated by the blower 25. 45 Thus, the finned tube 38 serves as a vapor condenser for condensing vapors accumulated within the casing 28 with the condensing action dependent upon operation of blower 25.

The blower driving motor 26 and the operating electromagnet 36a of valve 36 are interconnected

to be energized in parallel circuit from the supply lines L_1, L_2 , under the joint control of the electromagnetically operated relay 42 and the tilting mercury switch 19. The operating winding 42a for the relay 42 is energized under the control of the room thermostat 43 from the secondary of the voltage reducing transformer 44 having its primary connected across the supply lines L_1, L_2 .

Operation of Figs. 1 and 2

With the hot water boiler 11 in normal operation, the pressure bellows 18 will regulate the position of dampers 15 and 16 so as normally to maintain the boiler water at a predetermined temperature sufficient to supply the needs of the domestic hot water heater 21 both summer and winter as long as an adequate supply of coal or other fuel is provided. In the summer, both the electromagnetic valve 36 and the motor 26 are maintained deenergized by relay 42 as shown in Fig. 1 since no heat is required in the rooms. Under these conditions the valve 36 is open and the pressure equalizing pipe 35 is effective to equalize the pressure between the vapor space 34 and the interior of casing 28 so that the water level indicated by the dotted lines 31, 32 and 33 is maintained. As a result, the thermosiphon circulating circuit is broken and no heat is transferred from the boiler 11 to the exchanger 12. Moreover, due to the heat insulation around the loop 24a, little, if any, heat is released from the condenser formed by the finned tube 38.

Whenever heat is required in the rooms, the room thermostat 43 will close its contacts to energize the relay operating winding 42a and thereby close relay contact 42b. Then, in case the contacts of the tilting mercury switch 19 are closed in response to steam pressure, as shown in Fig. 1, the electromagnetic valve 36 will be energized so as to close and thereby interrupt the communication between the boiler vapor space 34 and the interior of casing 28. The energizing circuit for the electromagnetic valve 36 extends from the supply line L_2 through conductor 45, relay contact 42b, conductor 46, tilting mercury switch 19, conductor 47, the operating electromagnet 36a for closing valve 36, and conductors 48 and 49 to the other supply line L_1 .

At the same time the blower driving motor 26 is energized in parallel circuit with the electromagnet 36a through conductors 47 and 48. Hence, blower 25 is started into operation to circulate air through the duct 24 as indicated by the arrows in Fig. 2. As a result, condenser 38 will be cooled sufficiently to condense the vapors accumulated within the siphon casing 28, thereby reducing the pressure therein below that of the pressure existing in the vapor space 34. Consequently, the boiler water level 31 will fall and the water levels 32 and 33 in the conduits 29 and 39 will rise until the level 37 is reached inside the casing 28 where condenser 38 becomes partially flooded. Under these conditions the hydrostatic siphon circulation control 14 of the thermosiphon heat transfer system 10 is rendered effective so as to circulate hot water from boiler 11 through conduit 29, casing 28, conduit 30, finned coil 23 and return conduit 13. Hence, blower 25 will operate to circulate air through the finned coil 23 to be heated and thus transfer heat into the rooms. At the same time, air is being circulated through the loop 24a to cool the condenser 38 and thereby insure that the water level 37 is maintained within the siphon casing 28.

When the heated air circulating to the room

has raised the room temperature sufficiently to cause room thermostat 43 to open its contacts, then the relay operating winding 42a is deenergized and the relay contact 42b returns to its normally open position in which it is shown so as to deenergize both the electromagnetic valve 36 and the blower driving motor 26. Upon the opening of valve 36, the pressure within the casing 28 becomes equalized with that in the boiler vapor space 34. As a result, the water levels 32 and 33 again become aligned with the normal boiler water level 31. This enables the hydrostatic siphon 14 to break the thermosiphon water circulating circuit and thus prevents further transfer of heat from the boiler 11.

In the modified form of the invention shown in Fig. 3, any heat producing device, such, for example, as the thyratron tube 50 shown, is maintained at a desired normal operating temperature by means of a thermosiphon heat dissipating system controlled in accordance with the present invention. As shown, the thyratron tube 50 is surrounded by a tank or liquid container 51 having the finned heat dissipating coils 52 interconnected therewith through the inverted U-shaped hydrostatic circulation control siphon 53. The casing or tank 51 is filled to the level indicated by the dotted line 54 with a suitable heat transfer liquid whose vapor pressure, at the desired operating temperature of the thyratron tube 50, is above atmospheric pressure. For example, ethyl ether is a suitable liquid where an optimum operating temperature of approximately 50° C. or 122° F. is desired.

The inverted U-tube siphon 53 is provided with a tubular condenser 55 provided with fins for dissipating heat therefrom, and connected at the top to the interior of an expansible bellows 56 placed inside the protective casing 57 with a suitable weight 58 compressing the bellows. The bellows 56, tubular condenser 55 and the upper part of the inverted U-tube 53 are filled with a suitable non-condensable gas, such as nitrogen, at a pressure somewhat below that of the desired operating vapor pressure of the liquid filling the casing or tank 51 and the heat exchange coil 52.

A restricted pressure equalizing tube 60 is interconnected between the top of the tubular extension 61 from tank 51 and the tubular condenser 55 and is preferably provided with heat dissipating fins as indicated.

Operation of Fig. 3

The thermosiphon liquid circulating circuit is maintained broken by the empty siphon 53 during the warming-up period of the thyratron tube 50. However, when the ebullition temperature of the liquid surrounding the tube 50 is reached, then the vapor pressure in the tubular extension 61 will begin to exceed that of the non-condensable gas above the liquid in the top of the U-tube 53 and the tubular condenser 55. The pressure differential thus developed will depress the liquid level 54 in the tank 51 and will correspondingly raise the liquid level 59 in the inverted U-tube 53.

The restricted equalizing connection 60 will tend somewhat to prevent the variation in liquid level just described, but with tube 60 suitably restricted the rate of vapor generation within the tank 51, due to heating from the thyratron tube 50, will exceed the capacity of the equalizing tube 60.

As a result, the liquid level in the inverted U-tube 53 will rise and the mixture of vapor and

non-condensable gas above the liquid level will be forced into the tubular condenser 55. Here the vapor is largely condensed due to the heat dissipating action of the fins with which the tubular condenser 55 is provided. The non-condensable gas will be forced into the bellows 56.

When the liquid level 59 has risen in siphon 53 sufficiently to establish continuity of the thermosiphon circuit, the liquid will flow from the tank 51 through the inverted U-siphon 53 to the heat dissipating coil 52, and thereby provide a cooling effect on the circulated liquid sufficient to maintain the thyratron tube 50 at the desired operating temperature.

In case the cooling effect should become great enough to drop the temperature of the liquid in tank 51 below the desired operating temperature, then the vapor pressure in the tubular extension 61 will tend to fall below that of the gas in bellows 56. The weight 58 will therefore compress bellows 56 and cause the inert gas to be forced through the tubular condenser 55 into the inverted U-tube 53. As a result, the continuity of the thermosiphon circulating circuit will be interrupted with a corresponding reduction in the cooling action of the finned coils 52.

It will be apparent to those skilled in the art that this modified form of the invention is not limited to cooling a thyratron tube but may be applied with equal advantage to cooling other heat producing devices such, for example, as internal combustion engines or the like. In this latter case where a lower normal operating temperature is desired, methyl alcohol or other suitable liquid may be used as the circulating heat transfer medium.

What is claimed as new and desired to be secured by Letters Patent of the United States is:

1. In combination, a heat producing device, a liquid circulating system of the thermosiphonic type for dissipating heat therefrom, a liquid trap connected in said circulating system, means for introducing condensable vapor into said trap, and means including a condenser for condensing said vapor to vary the pressure in said trap and thereby control the thermosiphonic circulation in said system.

2. In combination, a heat producing device, a liquid circulating system of the thermosiphonic type for dissipating heat therefrom, said heat producing device including a container arranged to hold a body of liquid at a predetermined level therein with a vapor space above the liquid, a liquid trap connected in said circulating system, said trap having a vapor space connected with the vapor space of said heat producing device, means for introducing condensable vapor into said vapor spaces, and means including a condenser arranged to condense vapor in said trap for maintaining a predetermined pressure differential between said vapor spaces to control the thermosiphonic circulation in said system.

3. In combination, a heat producing device, a liquid circulating system of the thermosiphonic type for dissipating heat therefrom, a liquid trap connected in said circulating system for controlling the circulation therein, means for introducing condensable vapor into said trap to stop thermosiphon circulation therethrough and means for condensing said vapor to start the thermosiphon circulation.

4. In combination, a heated liquid container, a liquid circulating system of the thermosiphonic type for dissipating heat therefrom, said container being arranged to hold a body of liquid at

a predetermined level therein with a vapor space above the liquid, a liquid trap connected in said circulating system above said level, means including a vapor pressure equalizing connection between said container and said trap for introducing condensable vapor into said trap, and means for maintaining a predetermined pressure differential between the vapor in said container and the vapor in said trap to permit thermosiphonic circulation, said means including a vapor condenser for condensing the vapor in said trap.

5. In combination, with a heat producing device having a thermosiphon heat transfer medium circulating system for dissipating heat therefrom of a liquid trap connected in said circulating system and provided with control means including a valve for varying the level of the medium in said trap to start and stop the thermosiphon circulation.

20 6. In combination with a heat producing device having a thermosiphon heat transfer medium circulating system of a liquid trap connected in said circulating system and provided with thermodynamic control means including a vapor pressure equalizing connection having an electromagnetic control valve and a vapor condenser for varying the level of the medium in said trap to start and stop the thermosiphon circulation, and means including a thermostatic switch for controlling the energization of said valve.

7. In combination, a thermosiphon heat transfer liquid circulating system including a heated liquid container having a liquid level therein and a vapor space above said level, means including 35 a liquid trap extended above said level and having a vapor pressure equalizing connection with said vapor space, vapor condenser means for condensing vapor in said trap, and thermostatically controlled means for reversely unbalancing the effectiveness of said connection and said condenser to start and stop the thermosiphon circulation in said system.

8. In combination, a thermosiphon heat transfer liquid circulating system including a heated 45 liquid container having a liquid level therein and a vapor space above said level, means including a trap extended above said level and having a vapor pressure equalizing connection with said vapor space for stopping thermosiphon circulation 50 from said container, vapor condenser means for condensing vapor in said trap, and thermostatic means for rendering said condenser means effective and relatively ineffective.

9. In combination, a thermosiphon heat transfer liquid circulating system including a heated liquid container having a liquid level therein and a vapor space above said level, means including 55 a liquid trap extended above said level and having a vapor pressure equalizing connection with said vapor space for stopping thermosiphon circulation from said container, vapor condenser means for condensing vapor in said trap, and vapor pressure responsive means for rendering said condenser means effective and relatively ineffective.

10. In combination, a thermosiphon heat transfer system including a hot water boiler having a vapor space above the water level therein, firing control means for maintaining the water in said boiler at a predetermined temperature, means including a trap extending above the water level of said boiler and having a vapor pressure equalizing connection with said vapor space for stopping thermosiphon circulation from said 70 boiler, condenser means interconnected with said

trap for normally tending to condense vapor in said trap, and means including a thermostatic control valve for closing said equalizing connection to start said thermosiphon circulation.

11. In combination with a heat producing device having thermosiphon heat transfer medium circulating system for dissipating heat therefrom, of a liquid trap connected in said circulating system for controlling the circulation therein, means for introducing noncondensable gas into said trap to stop thermosiphon circulation therethrough, and pressure responsive means for withdrawing said noncondensable gas from said trap to start the thermosiphon circulation.

12. In combination with a heat producing device having a thermosiphon heat transfer medium circulating system for dissipating heat therefrom, of a liquid trap connected in said circulating system for controlling the circulation therein, means including a gas filled bellows connected with said trap and provided with biasing means for main-

taining a predetermined pressure therein to introduce gas into said trap to stop thermosiphon circulation therethrough, said bellows being responsive to the vapor pressure of said medium for withdrawing said gas from said trap to start the thermosiphon circulation when the temperature of said medium exceeds a predetermined value.
